COMBINED CLOCK, CALENDAR AND CABINET FOR EYEGLASSES

Chester M. MacChesney, Chicago, and Richard Winkler,
Palos Heights, Ill., assignors to Ellamac Incorporated,
a corporation of Illinois

Filed Oct. 17, 1966, Ser. No. 4,310

Term of patent 7 years

(Cl. D42—7)

FIG. 1

FIG. 2

FIG. 3**FIG. 4**FIG. 1 is a front perspective view of a combined clock, calendar and cabinet for eyeglasses showing our new design;

FIG. 2 is a side elevational view;

FIG. 3 is a front perspective view, with the cover member in open position, and a pair of eyeglasses shown in broken lines for illustrative purposes only; and

FIG. 4 is a rear elevational view on a slightly reduced scale.

We claim:

The ornamental design for a combined clock, calendar and cabinet for eyeglasses, as shown and described.
